UNITED STATES PATENT OFFICE.

WILBUR G. FRINK, OF MIDDLETOWN, NEW YORK, ASSIGNOR TO THE BORDEN COMPANY, OF NEW YORK, N. Y., A CORPORATION OF NEW JERSEY.

SPRAYING DEVICE.

Application filed May 13, 1925. Serial No. 29,912.

The invention relates to an improvement in spraying devices for washing can covers and the like.

By reason of their peculiar shape considerable difficulty has been experienced in effectively cleansing the covers of the large cans used for the transportation of fluid milk. The object of the present invention is to produce a spraying device for washing can covers and the like so constructed and arranged as to assure a rapid and thorough cleansing of the can covers or other articles. To this end the invention consists in the improved spraying device hereinafter described and particularly pointed out in the claims.

In the accompanying drawings illustrating the preferred form of the invention, Fig. 1 is a plan view of the improved spraying device and shows its relation to the runway along which the can covers are advanced into and through the device; Fig. 2 is a side elevation, partly in section, of the spraying device shown in Fig. 1; and Fig. 3 is an enlarged transverse section through a portion of the spraying device, illustrating particularly the spray perforations.

The improved spraying device, as illustrated in the drawings, is especially adapted for use in cleansing can covers of the usual "umbrella" type, shown in section at 5 in Fig. 2. This can cover 5 comprises a cylindrical body portion 6 adapted to fit within the neck of the usual forty quart can used for the transportation of fluid milk. The upper end of the cylindrical portion 6 of the can cover is closed by a depressed disc portion 7, the outer edges of which project outwardly and downwardly as a curved flange or umbrella-like portion 8. Although the illustrated embodiment of the improved spraying device is particularly adapted for washing this type of can cover or like utensil, it will be understood that the invention is not to be restricted to this use, inasmuch as it is equally adapted with obvious changes for use in cleansing various kinds of utensils.

The improved spraying device comprises a cylindrical head 10 which may conveniently be of substantially the same diameter as the can cover 5. The head 10 is a hollow structure, as indicated by the dotted lines 11 in Fig. 2, and is adapted to be supplied with water or other washing fluid under pressure

through the pipe 12 screwed into the threaded port 13. The open lower end of the hollow head 10 is closed by a bottom cover 14. The laterally projecting flange 15 of the head 10 is provided with four bosses 16 which align with four bosses 17 projecting laterally from the rim of the cover 14. The bolts 18 loosely received in the bosses 17 and screwed into the bosses 16 secure the cover 14 to the head 10.

The upper portion of the spray head 10 consists of two series of opposed steps at various levels, as shown in Fig. 2, so as thereby to accommodate conveniently the can covers or other articles to be washed and bring the surfaces to be cleansed relatively close to the orifices or perforations through which the washing fluid is ejected. The upper steps 20 and 21 are spaced apart so that the cylindrical portion 6 of the covers may pass freely between them. The upper surfaces of the steps 20 and 21 are provided with the perforations 22 arranged at various angles by which the washing fluid is directed into the annular concavity under the umbrella-like portion 8 of the covers. The intermediate steps 23 and 24 are provided at their upper surfaces with the perforations 25 arranged at various angles, as clearly shown in Fig. 3, so that the wash fluid may reach the entire inner surfaces of the cover constituted by the disc portion 7 and the cylindrical portion 6. The perforations in the step 23 direct the wash fluid to one inner side of the can cover and the perforations in the step 24 direct the wash fluid to the other inner side of the can cover. The steps 23 and 24 are spaced apart to provide space for the sprays from the angularly arranged perforations 26 in the bottom steps 27 and 28. The perforations 26 direct wash fluid only to the under surface of the disc-like portion 7 of the can covers. It will be observed by reference to Fig. 2 that the perforations 25 and 26 are so arranged as to effectively direct the sprays of wash fluid against every part of the entire interior surface of the cylindrical portion of the cover.

The can covers are successively brought to rest over the spray head 10 by means of a cover-engaging finger 30 yieldingly mounted on an intermittently reciprocating bar 31 located in the longitudinal recess 32 between the steps 27 and 28. The reciprocating bar 31 and finger 30 operate in the usual

manner and need no further description. The can covers are supported on the guide rails or rods 33 and 34 secured to the inner opposed faces of the steps 23 and 24. The 5 upper edges of the rods 33 and 34 are substantially flush with the upper surfaces of the steps 23 and 24 and for the purposes of this invention may be regarded as forming part of the steps 23 and 24. The covers are 10 guided laterally by means of the rails or rods 36 and 37 secured to the inner opposed faces of the upper steps 20 and 21.

The improved spraying device of the present invention is designed to constitute a unit 15 in a series of such devices acting in conjunction and synchronously with devices arranged to wash and sterilize the insides of the cans to which the covers belong. In practice, each cover accompanies its can 20 through the washing apparatus so that when they emerge therefrom the operative may place each cover on its respective can.

Having thus described the invention what I claim as new is:—

25 1. A spraying device for washing can covers and the like comprising, a hollow head adapted to be supplied with wash fluid under pressure, the upper portion of the head consisting of two series of oppositely disposed steps, the upper pair of steps being spaced apart for the passage between them of the cylindrical portion of the cover, a lower pair of steps being adapted to receive and support the lower edge of the cover, the 30 upper surfaces of the steps being provided with perforations arranged at various angles to direct sprays of wash fluid at different parts of the under surfaces of the covers.

2. A spraying device for washing can 40 covers and the like comprising, a hollow head adapted to be supplied with wash fluid under pressure, the upper portion of the head consisting of a plurality of oppositely disposed steps at various levels arranged to support a can cover, the upper surfaces of each step being provided with perforations for directing sprays of wash fluid against the under surfaces of the can cover.

3. A spraying device for washing can 50 covers consisting of an umbrella-shaped top having depending therefrom a cylindrical portion, said spraying device consisting of a head and means for supplying the head with washing fluid, the upper portion of said

head consisting of a plurality of steps, the 55 upper steps being opposed and spaced apart to accommodate the cylindrical portion of the cover, and a lower pair of steps being arranged to support the lower edge of the cylindrical portion of the cover, the upper 60 surfaces of said steps being provided with perforations arranged at various angles for directing sprays of wash fluid against the under surfaces of the cover.

4. A spraying device for washing can 65 covers consisting of a cylindrical portion having a closed upper end with the outer edges thereof extending outwardly and downwardly, said spraying device comprising a head adapted to be supplied with wash 70 fluid, the upper portion of the head consisting of a series of surfaces at different levels, the upper surfaces being spaced apart to accommodate the cylindrical portion of the cover and having perforations for directing sprays of wash fluid against the under surface of the flange of the cover, the other surfaces being provided with perforations for directing sprays of wash fluid 75 against the interior of the enclosed cylindrical portion of the cover.

5. A spraying device for washing can 80 covers and the like comprising, a hollow head adapted to be supplied with wash fluid under pressure, the upper portion of said head consisting of two series of opposed steps spaced apart to permit a can cover to be advanced between them, one pair of steps being provided with guide rods for supporting the lower edge of the cover, another pair of steps being spaced apart to accommodate the sides of the cover, and the lowermost pair of steps being spaced apart to accommodate the means for advancing the cover through the device, the upper surfaces of all 90 said steps being perforated for directing sprays of wash fluid against the under surface of the cover.

6. A spraying device for washing articles comprising, a hollow head adapted to be 100 supplied with wash fluid under pressure, the upper portion of the head consisting of pairs of steps at various levels to accommodate the article to be washed, the upper surfaces of the steps being perforated to direct sprays 105 of wash fluid against the under surface of the article.
